Hazeltine Corporation, a corporation of Dela-
ware

Application August 12, 1933, Serial No. 684,827

28 Claims. (Cl. 250—20)

The present invention relates to a selective circuit, and more particularly to an adjustably selective system designed to respond simultaneously to two or more widely separated frequencies.

The system includes appropriately selective, inductively reactive and capacitively reactive elements, so arranged and connected in the system that adjustment of a single variable element produces two points of maximum impedance widely separated and bearing a fixed law of variation with respect to each other as the variable element is adjusted over a substantial range. In its fundamental aspect, the circuit may be considered as a tuned circuit having two oscillatory periods widely separated and moving simultaneously as the adjustable element is varied.

It is the object of this invention to produce a circuit which may be tuned to two different frequencies, by means of a single variable element.

It is a further object of this invention to produce a system in which a single variable element may be utilized to tune said system to simultaneously vary two resonance frequencies for supplying voltage corresponding to each of the oscillatory periods, to a plurality of vacuum tubes, thus providing a selective input system for each of said tubes, which system requires a single adjustable element.

It is another object of this invention to provide a modulation of frequency-changing circuit for the input of a superheterodyne, which requires a single variable condenser to simultaneously tune to the desired signal and oscillation frequency.

These, and further objects of this invention, will become apparent from the following specification and claims taken in connection with the accompanying drawings.

In accomplishing the object of this invention, with particular reference to a superheterodyne radio receiver for the purpose of illustration, the signal frequency tuned input circuit of the first detector or modulator of the superheterodyne receiver, is tuned by a variable condenser in the usual manner to receive audio-modulated carrier waves. The oscillation-frequency-determining circuit, or oscillation circuit, as it will be referred to hereinafter, is so connected in shunt across the signal-frequency tuned circuit, or signal circuit, as it will be referred to hereinafter, that the same variable condenser may be utilized to tune the oscillation circuit. A high intermediate frequency is chosen so that the tuning of each of

the two circuits will have relatively no effect upon the voltages developed in the other of the two circuits. In other words, a high-frequency difference is selected so that the tuning inductance of the signal-frequency circuit will act as a choke at the oscillation frequency. Similarly, with a high difference, the auxiliary alignment condenser and the oscillation-frequency inductance will constitute a high impedance in this path at the signal frequency.

Having thus briefly described the invention, attention is invited to the accompanying drawings in which:

Fig. 1 is an elementary circuit diagram of the fundamental circuit comprising the present invention;

Fig. 2 is a circuit diagram of a superheterodyne radio receiver, including a frequency-changing circuit, constructed in accordance with this invention;

Fig. 3 is a diagram of a circuit similar to that of Fig. 2, but including an additional radio-frequency amplifier before the frequency-determining circuit; and,

Fig. 4 is a diagram of a similar selective circuit, in which a single tube is utilized to act as both oscillator and modulator.

Referring now more particularly to Fig. 1 of the drawings, an input circuit connected to a source of high frequency, includes a primary inductance L_1 which is inductively coupled to a secondary inductance L_2 , included in the tunable oscillatory circuit 14. The circuit 14 may include an additional inductance L_2' and variable condenser C_2 , by means of which the resonance frequency of the circuit 14 may be adjusted. In shunt with the variable condenser C_2 is connected the tunable circuit 18, which includes condenser C_3 , inductance L_3 and condenser C_4 , which, together with C_3 , constitutes a second tunable oscillatory circuit. The input of tube 16 includes the tunable circuit 14, and the input of the tube 17 includes the inductance L_3 of the tunable circuit 18.

In operation, the characteristics of the various elements of tunable circuits 14 and 18 are so chosen that a wide frequency difference will exist between the resonance periods of each of these circuits, the frequency of the tunable circuit 18 being higher than that of the tunable circuit 14. At the high resonant-frequency of the circuit 18, the total inductance of circuit 14 will act as a high-frequency choke, and at the lower resonant-frequency of the circuit 14, the capacities C_3 and C_4 will act as a high impedance. Furthermore,

the series capacity C_3 and C_4 of circuit 18, act to limit the tuning range of the condenser C_2 with respect to the tunable circuit 18, by means of which the variation of the condenser C_2 serves to simultaneously tune the two circuits 14 and 18 in the same sense to low and relatively high radio frequencies, respectively, and over substantially equal frequency ranges. It is obvious that voltages of both frequencies will exist across the condenser C_2 and therefore voltages of both frequencies may be supplied to the input of tube 15. However, the input of tube 17 is connected across the inductance L_3 and therefore is substantially isolated from the circuit 14, and consequently, the tube 17 responds merely to the frequency of the tunable circuit 18. Furthermore, since circuit 14 is parallel-resonant with respect to condenser C_2 and circuit 18 is parallel-resonant with respect to inductance L_3 , an impedance maxima will appear across condenser C_2 at the resonant frequency of circuit 14 and across inductance L_3 at the resonant frequency of circuit 18.

A particular application of this circuit to a superheterodyne radio receiver is illustrated in Fig. 2, in which corresponding elements are designated by the same reference characters.

In Fig. 2, the antenna circuit includes the antenna 11, ground 12, and input primary inductance L_1 . The inductance L_1 is inductively coupled to the inductance L_2 of the signal circuit 14, which circuit is tuned to resonance with the desired signal frequency by the variable condenser C_2 . The signal frequency voltage developed across the condenser C_2 is impressed between the control grid and cathode of the modulator tube 15, which may be of the pentode type as, for instance, the type 58. A grid-biasing resistor R_5 is included in the cathode lead of the tube 15 for the purpose of providing the proper grid bias, and a radio-frequency by-pass condenser C_5 is provided in shunt with the biasing resistor.

The oscillator tube 17, which may be of the triode type, as for instance type 56, has the oscillation circuit 18 connected between its grid and cathode.

The oscillation circuit 18 comprises in series the inductance L_3 , the alignment condenser C_3 , the variable condenser C_2 , which is common to the tuned input circuit 14, and condenser C_4 .

The oscillation frequency is controlled by the variable condenser C_2 , the capacity range of which is limited relative to its effect upon the oscillation frequency by the alignment condenser C_3 and to some extent by by-pass condenser C_4 . A padding condenser C_6 , for assisting the alignment, is connected between the junction of inductance L_3 with condenser C_3 and ground, and is, therefore, substantially in shunt with the inductance L_3 . The resistor R_4 is for the purpose of providing the proper bias on the grid of the oscillator tube 17. The bias is produced by the grid current and limits the oscillation amplitude.

The plate electrode of the tube 17 is connected through the coupling resistor R_2 to a source of high potential indicated as the battery 16. A radio-frequency by-pass condenser C_7 is provided across the battery 16.

The radio-frequency voltage fluctuations, which are developed across R_2 , are impressed upon the oscillation circuit by the feed-back circuit which includes the connection through the condenser C_6 to the lower end of the inductance L_4 and the blocking condenser C_4 . The inductances L_3 and L_4 are inductively coupled, thus providing an electromagnetic coupling between the feed-back cir-

cuit of the oscillator tube 17 and the oscillation circuit. The condenser C_4 is common both to the feed-back and oscillation circuits and, therefore, may provide additional coupling between these two circuits.

That portion of the oscillation voltage which is impressed across the condenser C_2 will be impressed upon the input of the modulator or first detector tube 15 and thus be combined in the input of said tube with received radio-frequency signal voltages which are also built up across the condenser C_2 . The bias of the tube 15 is so arranged that it will act as a modulator, and an audio-modulated intermediate frequency will be produced in the output circuit of the modulator 15 tube.

The output circuit of the modulator tube 15 includes the radio-frequency choke L_5 and the high-voltage source 16. The screen grid of the modulator tube 15 may be supplied with the appropriate voltage by means of a tap in the battery 16. The high-voltage source 16 is by-passed for high frequencies by means of condenser C_7 . That portion of battery 16 which supplies the screen grid potential may be similarly provided with a by-pass condenser C_8 .

The intermediate-frequency voltage developed across the choke L_5 is coupled through condenser C_9 to the input of the intermediate-frequency responsive radio receiver 20 by which it is further amplified, detected and reproduced in the usual manner by the loudspeaker 21. The details of the remainder of the receiver and reproducer are common to those found in the art and, therefore, need no further description.

The oscillation-frequency voltages impressed across the inductance L_2 may be transferred capacitively, or inductively to the antenna primary inductance L_1 . Therefore, to prevent radiation of the oscillation-frequency voltages, a neutralization arrangement may be provided as shown. This system comprises the connection between the lower end of the feed-back coil L_4 through the neutralizing condenser C_1 to the upper end of the antenna primary inductance L_1 . The neutralizing capacity C_1 is so adjusted that the feed-back of the oscillation-frequency voltage to the upper end of the coil L_4 is just sufficient to neutralize that transferred thereto by the tuning inductance L_2 .

Appropriate cathode heating circuits may be provided and these, together with the voltage source represented by the battery 16, may be the same as those provided for supplying the various voltages required in the receiver 20.

As above stated, the oscillation frequency chosen should be considerably higher than the frequency of the signals which it is desired to receive. For instance, an intermediate or difference frequency of 4800 kilocycles may be selected, in which event, in order to cover the broadcast band of from 550 kilocycles to 1500 kilocycles, the oscillation-frequency circuit 18 must tune through a band of from 5350 kilocycles to 6300 kilocycles. Therefore, the percentage variation of capacity required to tune the oscillation inductance L_3 through this range of frequencies being rather small, the condenser C_3 may be of such low capacity that it will present a very high impedance to voltages of the signal frequency. In other words, there will be but slight loss of signal-frequency voltage through the condenser C_3 and inductance L_3 , which are in shunt with the inductance L_2 . The impedance of the inductance L_2 , which is in shunt with the condenser C_2 across 75

which voltages of the oscillation frequency are developed, is so high relative to oscillation-frequency voltages that it will have a negligible effect on these voltages.

5 Thus, an arrangement has been produced in which the single condenser C_2 may be utilized to tune two inductances to considerably different frequencies, and the voltages of the two frequencies which are developed across the single variable 10 condenser may be impressed upon the input of the modulator tube 15 and there combined to produce the modulated intermediate frequency in the usual manner.

15 The condenser C_3 acts, as has been stated above, to limit the range of the condenser C_2 and thus acts as an alignment condenser by means of which the difference between the frequency of the signal currents and the frequency of the oscillation currents may be maintained substantially 20 uniform as the condenser C_2 is varied to tune the input circuit throughout the tuning range. The padding condenser C_p permits a three point adjustment of alignment to be obtained. The padding condenser, C_p , is adjusted to correct the 25 alignment when tuned to the upper end of the broadcast band. The inductance L_3 is adjusted to give correct alignment in the middle of the band, and the condenser C_3 is adjusted to correct the alignment at the low-frequency end of the 30 band. These three adjustments are mutually dependent, but when properly made the circuits will maintain their alignment as the condenser C_2 is tuned over its range. Although condenser C_4 is 35 a blocking condenser and has such large capacity as to affect but slightly the tuning of the oscillation circuit, its capacity may be so chosen as to assist in maintaining the alignment, as well as to assist in maintaining uniform oscillation voltages.

40 Although the various elements of the circuit shown may have a wide variety of characteristics, the following approximate values have been found to be satisfactory in producing an oscillator and modulator system which will operate to receive signals in the broadcast band extending 45 from 550 kilocycles to 1500 kilocycles using an intermediate frequency of 4800 kilocycles:

50 Inductance $L_1=1$ mh.
Inductance $L_2=.2$ mh.
Inductance $L_3=.015$ mh.
Inductance $L_4=.015$ mh.
Condenser $C_2=20$ mmf.-500 mmf.
Condenser $C_3=30$ mmf.
Condenser $C_4=.1$ mf.
Condenser $C_5=.001$ mf.
Condenser $C_p=10$ mmf.
Resistor $R_2=50,000$ ohms.
Resistor $R_4=20,000$ ohms.

60 Although any appropriate tubes may be used in the circuit described above, a type 58 has been found appropriate for use as the modulator 15, and a type 56 has been found to be appropriate for use as the oscillator tube 17.

65 Figure 3, to which attention is now invited, shows a similar frequency-changing circuit for use in a superheterodyne receiver. In this figure, parts corresponding to those shown in Fig. 2 are designated by the same reference characters. In 70 this circuit, however, an additional radio-frequency amplifier is provided between the antenna and the modulator tube 15. This circuit comprises the usual radio-frequency tuned circuit 7 which is inductively coupled to the inductance 75 L_1 of the antenna circuit and connected in the

input of the radio-frequency amplifier tube 8. The output of the amplifier tube 8 includes primary inductance L_1 , which corresponds to the antenna inductance L_1 of Fig. 1. This primary inductance is inductively coupled to the secondary inductance L_2 of the signal-frequency circuit 14. With this arrangement, the necessity for the neutralizing condenser C_1 of Fig. 2 is obviated, as the oscillator-frequency voltages impressed across the inductance L_2 will be effectively blocked by the unilateral transmission characteristics of the screen grid tube 8. The tube 8 may for instance be a pentode, as shown, although any other suitable tube may be used. It is obvious, of course, that the input of the tube 8 might be untuned, in which event the tube would constitute a coupling tube. The condenser of the tuned circuit 7 may be connected as shown, to be operated in a uni-control manner with the condenser C_2 of the radio-frequency tuned circuit 14.

5

20

The output of the modulator is impressed upon the input of the intermediate frequency amplifier of the receiver 20 by means of the tuned intermediate frequency transformer 19, the primary L_5' of which is included in the plate circuit of 25 the tube 15.

25

30 Appropriate voltage sources may be provided for the operation of the amplifier tube 8, and these sources may be combined with those providing the voltages for the remainder of the circuit shown.

35 Attention is now invited to Fig. 4, which shows a similar frequency-changing circuit in which a single tube performs the function of oscillator and modulator, corresponding parts being designated by the same reference characters. In the circuit shown, the tube 15' is of the virtual cathode electron coupled type. Any other type of oscillator-modulator may be used if desired. As shown, the tuned input circuit 14 is connected 40 to number four grid, and this grid, the plate, and a virtual cathode, positioned just inside the number three grid, act as an electron-coupled modulator. Number two grid acts as the oscillator anode, and is connected through resistor 45 R_2 to the voltage source 16. The second grid circuit comprises the condenser C_3 , inductance L_4 , and condensers C_4 and C_5 . This circuit is coupled to the oscillation circuit 18 by means 50 of the inductive coupling between inductance L_4 and inductance L_3 and by the capacitive coupling of the condenser C_4 which is common to these circuits. The oscillation voltage is impressed upon the first grid, to which it is directly connected. In operation, the first grid voltage controls the cathode emission, and the signal voltage impressed on the fourth grid controls the portion of this emission which reaches the plate. This voltage, however, is powerless to affect the 55 voltage of the first grid. The operation is otherwise similar to that of the circuits shown in Figs. 2 and 3.

60

65 Whereas the invention has been described as a frequency changer for a superheterodyne radio receiver, it may be utilized as the frequency changer for any heterodyne reception system, and it is equally applicable to frequency changers for use in connection with the production of radiant energy for any purpose, or to any system in which it is desired to tune two resonant circuits over a range in frequency, maintaining a constant frequency interval between them and using only one variable reactance element.

70

75 I claim:

1. A frequency-changing circuit which includes

75

- a modulator tube and an oscillator tube, each of said tubes having input and output terminals, a first tuned circuit connected to the input terminals of one of said tubes and tunable to a desired frequency, said circuit comprising an inductance and a variable condenser, a second tuned circuit connected across the input terminals of the other of said tubes and tunable to a different frequency, said last-mentioned circuit including a second inductance, a fixed condenser and said first-mentioned variable condenser and having reactive constants so proportioned with respect to those of said first circuit that each of said circuits has a high impedance to currents of the frequency to which the other is resonant, and a coupling between the output of said oscillator tube and the tuned circuit connected to the input thereof, whereby the resonant frequency of each of the tuned circuits is controlled by a single variable condenser to tune said circuits through a band in frequency.
2. A frequency-changing circuit which includes a modulator tube and an oscillator tube, each of said tubes having input and output terminals, an input circuit, a first tuned circuit, coupled to said input circuit, connected to the input terminals of one of said tubes, and tunable to a desired frequency, said circuit comprising an inductance and a variable condenser, a second tuned circuit connected across the input terminals of the other of said tubes and tunable to a different frequency, said circuit including a second inductance, a fixed condenser and said first-mentioned variable condenser and having reactive constants so proportioned with respect to those of said first circuit that each of said circuits has a high impedance to currents of the frequency to which the other is resonant, a coupling between the output of said oscillator tube and the tuned circuit connected to the input thereof for producing oscillations of a frequency determined by said circuit, and means for neutralizing the oscillation-frequency voltage developed in said input circuit, whereby the resonant frequency of said circuits is controlled by a single variable condenser to tune each of said circuits through a band in frequency.
3. A frequency-changing circuit which includes a modulator tube and an oscillator tube, each of said tubes having input and output terminals, a first tuned circuit connected to the input terminals of one of said tubes and tunable to a desired frequency, said circuit comprising an inductance and a variable condenser, a second tuned circuit connected across the input terminals of the other of said tubes and tunable to a different frequency, said second circuit including a second inductance, a fixed condenser, and said first-mentioned variable condenser and having reactive constants so proportioned with respect to those of said first circuit that each of said circuits has a high impedance to currents of the frequency to which the other is resonant, and a dual coupling between the output of said oscillator tube and the tuned circuit connected to the input thereof, whereby the resonant frequency of each of said tuned circuits is controlled by a single variable condenser to tune said circuits through a band in frequency.
4. A frequency-changing circuit which includes a modulator tube and an oscillator tube, each of said tubes having input and output terminals, a first tuned circuit connected to the input terminals of one of said tubes and tunable to a desired frequency, said circuit comprising an inductance and a variable condenser, a second tuned circuit connected across the input terminals of the other of said tubes and tunable to a different frequency, said second circuit including a second inductance, a fixed condenser, and said first-mentioned variable condenser and having reactive constants so proportioned with respect to those of said first circuit that each of said circuits has a high impedance to currents of the frequency to which the other is resonant, and a combined electromagnetic and electrostatic coupling between the output of said oscillator tube and the tuned circuit connected to the input thereof, whereby the resonant frequency of each of said tuned circuits is controlled by said variable condenser to tune said circuits through a band in frequencies.
5. A radio-frequency circuit comprising a first tuned circuit, tunable over a desired range of radio frequencies and comprising an inductance and a variable condenser, and a second tuned circuit, tunable over a different range of radio frequencies and including a second inductance, a fixed condenser, and said first-mentioned variable condenser and having reactive constants so proportioned with respect to those of said first circuit that each of said circuits has a high impedance to currents of the frequency to which the other is resonant, and a combined electromagnetic and electrostatic coupling between the output of said oscillator tube and the tuned circuit connected to the input thereof, whereby the resonant frequency of each of said tuned circuits is controlled by said variable condenser to tune said circuits through a band in frequencies.
6. A radio-frequency circuit comprising a first tuned circuit, tunable over a desired range of radio frequencies and comprising an inductance and a variable condenser, and a second tuned circuit, tunable over a different range of radio frequencies and including a second inductance, a fixed condenser, and said first-mentioned variable condenser and having reactive constants so proportioned with respect to those of said first circuit that each of said circuits has a high impedance to currents of the frequency to which the other is resonant, said second inductance and said fixed condenser being so proportioned that a variation of the capacity of said variable condenser will tune both of said circuits throughout a range in frequency and maintain a substantially constant frequency difference between the frequencies of each of said circuits, whereby the frequencies of both of said circuits may be simultaneously controlled by a variation of the capacity of said variable condenser.
7. A radio-frequency circuit comprising a first tuned circuit, tunable over a desired range of radio frequencies and comprising an inductance and a variable condenser, and a second tuned circuit, tunable over a different but substantially equal range of radio frequencies and including a second inductance, a fixed condenser, and said first-mentioned variable condenser, said second inductance and said fixed condenser being so proportioned that each of the circuits will have a high impedance to currents of the frequency to which the other is resonant, whereby both of said circuits may be simultaneously tuned by variation of the capacity of said variable condenser.
8. A radio-frequency circuit comprising a first tuned circuit, tunable over a desired range of radio frequencies and comprising an inductance and a variable condenser, and a second tuned circuit, tunable over a different range of radio frequencies and including a second inductance, a fixed condenser, and said first-mentioned variable condenser, said second inductance and said fixed condenser being so proportioned that each of the circuits will have a high impedance to currents of the frequency to which the other is resonant, and will resonate to a frequency having a definite substantially fixed relation to the frequency to which the other circuit resonates as both of said circuits are simultaneously tuned through a band in frequency by a variation of the capacity of said variable condenser.
9. A radio-frequency circuit comprising a first tuned circuit, tunable over a desired range of radio frequencies and comprising an inductance and a variable condenser, and a second tuned circuit, tunable over a different range of radio frequencies and including a second inductance, a fixed condenser, and said first-mentioned variable condenser, said second inductance and said fixed condenser being so proportioned that each of the circuits will have a high impedance to currents of the frequency to which the other is resonant, and will resonate to a frequency having a definite substantially fixed relation to the frequency to which the other circuit resonates as both of said circuits are simultaneously tuned through a band in frequency by a variation of the capacity of said variable condenser.

5   quencies and including a second inductance, a fixed condenser and said first-mentioned variable condenser, said second inductance and said fixed condenser being so proportioned that each of the circuits will have a high impedance to currents of the frequency to which the other is resonant and will resonate to a frequency having a substantially constant frequency difference relative to the frequency to which the other circuit resonates as both of said circuits are simultaneously tuned through a band in frequency by a variation of the capacity of said variable condenser.

10   9. A radio-frequency circuit comprising a first tuned circuit, tunable over a desired range of radio-frequencies and comprising an inductance and a variable condenser, and a second tuned circuit, tunable over a different but substantially equal range of radio frequencies and including a second inductance, a fixed condenser and said first-mentioned variable condenser, said fixed condenser being so chosen that it will act as a high impedance to currents of the frequency of the first tuned circuit, and the elements of said second circuit being so chosen as to cause said circuit to be resonant to a frequency to which the first-mentioned inductance has a high impedance, whereby each of said circuits will resonate at a distinct frequency without affecting the voltages in the other circuit.

15   10. A frequency-changing circuit which comprises a first tuned circuit, tunable to the frequency of a current which it is desired to modulate and comprising an inductance and a variable condenser, a second tuned circuit tunable to the frequency of a modulating current, and including a second inductance, a fixed condenser, and said first-mentioned variable condenser, and a modulator tube including input terminals, said input terminals being connected across said variable condenser, said variable condenser serving to impress voltages representative of both of said currents upon the input of said modulator tube and simultaneously controlling the resonance frequency of said circuits.

20   11. A frequency-changing circuit comprising a first tuned circuit, tunable to the frequency of a current it is desired to modulate, and comprising an inductance and a variable condenser, a second tuned circuit tunable to the frequency of a modulating current, and including a second inductance, a fixed condenser, and said first-mentioned variable condenser, a modulator tube including input terminals connected across said variable condenser, means for supplying current of one of said frequencies to said first tuned circuit, and means for supplying an oscillation-frequency voltage to said second tuned circuit, whereby voltages of both of said frequencies may be impressed upon the input of said modulator tube by said variable condenser, said condenser serving simultaneously to control the resonance frequency of both of said circuits.

25   12. A frequency-changing circuit comprising a first tuned circuit, tunable to a desired signal frequency and comprising an inductance and a variable condenser, a second tuned circuit, tunable to an oscillation frequency and including a second inductance, a fixed condenser, and said first-mentioned variable condenser, a modulator tube having its input terminals connected across said variable condenser, an oscillator tube including input and output terminals, said input terminals being connected across the inductance of said second tuned circuit, and a feed-back circuit connected to the output terminals of said oscil-

30   lator tube, whereby voltages of said signal frequency and said oscillation frequency are impressed upon the input terminals of said modulator tube by said variable condenser, which condenser serves to simultaneously control the resonance frequency of each of said circuits.

35   13. A frequency-changing circuit comprising a first tuned circuit, tunable to the frequency of a desired current it is desired to modulate and comprising an inductance and a variable condenser, a second tuned circuit, tunable to an oscillation frequency and including a second inductance, a fixed condenser, and said first-mentioned variable condenser, said second inductance and said fixed condenser being so proportioned that a variation 15 of the capacity of said variable condenser will tune both of said circuits through a range in frequency and maintain a substantially constant difference between the frequencies of said circuits, and a modulator tube having its input terminals coupled to both of said circuits, whereby voltages of the frequency of both of said circuits are impressed upon the input of said modulator tube.

40   14. A frequency-changing circuit which comprises a first tuned circuit, tunable to a desired radio frequency and comprising an inductance and a variable condenser, a second tuned circuit, tunable to an oscillation frequency and including a second inductance, a fixed condenser, and said first-mentioned variable condenser, said second inductance and said fixed condenser being so proportioned that a variation of the capacity of said variable condenser will tune both of said circuits throughout a range in frequency and maintain a substantially constant frequency difference between the frequencies of the current in each of said circuits, means for producing an oscillation-frequency voltage in the second tuned circuit, and a modulator tube having its input terminals connected across said variable condenser, whereby voltages of two frequencies, as controlled by variation of the capacity of said variable condenser, are impressed upon the input 45 of said modulator tube.

45   15. A frequency-changing circuit which comprises a first tuned circuit tunable to a desired signal frequency and comprising an inductance and a variable condenser, a second tuned circuit, tunable to an oscillation frequency and including a second inductance, a fixed condenser and said first-mentioned variable condenser, said second inductance and said fixed condenser being so proportioned that a variation of the capacity of said variable condenser will tune both of said circuits throughout a range in frequency and maintain a substantially constant frequency difference between the currents in each of said circuits, a modulator tube having its input connected across 50 said variable condenser, an oscillator tube having its input terminals connected across said second inductance, and a feed-back circuit connected between the output terminals of said oscillator tube and coupled to said second tuned circuit for producing oscillation frequency currents in said second tuned circuit, whereby there is produced in the output of said modulator tube a signal-modulated intermediate frequency having a substantially constant frequency as said variable condenser is tuned to receive signals covering a band 55 in frequency.

60   16. A frequency-changing circuit which includes a first vacuum tube having input and output terminals, a first tuned circuit connected across 65

70   75

the input terminals of said first vacuum tube and tunable to a radio frequency, said circuit including an inductance and a variable condenser, a second tuned circuit connected in shunt with said variable condenser and including in series 5 a first fixed condenser, a second inductance, and a second fixed condenser, said fixed condensers and said second inductance being so proportioned that said second tuned circuit will resonate at a 10 constant frequency difference from the frequency of the first tuned circuit as said variable condenser is varied to tune both of said circuits through a range in frequency, a second tube including input and output terminals, connections 15 from one end of said second inductance and the junction of said variable condenser and said second fixed condenser to the input terminals of said second tube, and a feed-back circuit connected to the output terminals of said second 20 tube for providing a dual feed-back coupling to said second tuned circuit, said feed-back circuit including in series, a feed-back condenser, a third inductance, inductively coupled to said second inductance, and said second fixed condenser, where- 25 by voltages of the frequency of both of said tuned circuits, as controlled by said variable condenser, are impressed upon the input of said first-mentioned tube.

17. A frequency-changing circuit which includes a modulator tube having input and output terminals, a signal-frequency circuit connected across said input terminals and including an inductance tunable by a variable condenser to the frequency of the current to be modulated, an 30 oscillation circuit connected in shunt with said variable condenser and including in series a first fixed condenser, a second inductance, and a second fixed condenser, said fixed condensers and said second inductance being so proportioned that 35 said oscillation circuit will resonate at a constant frequency difference from the frequency of the signal-frequency circuit as said variable condenser is varied to tune said signal-frequency circuit throughout a range in frequency, an oscil- 40 lator tube including input and output terminals, connections from one end of said second inductance and the junction of said variable condenser and said second fixed condenser to said input terminals, and a feed-back circuit connected to 45 the output terminals of said oscillator tube for providing a dual coupling to said oscillation circuit, said circuit including in series a feed-back condenser, a third inductance, inductively coupled to said second inductance, and said second 50 fixed condenser, whereby voltages of the frequency of a signal current and an oscillation current, the frequencies of both of which are determined by said variable condenser, are impressed across said variable condenser and upon 55 the input of said modulator tube, and whereby a signal-modulated difference frequency voltage is produced in the output circuit of said modulator tube.

18. In a frequency-changing circuit, tuned 60 circuits tunable to the frequency of a signal-frequency to be modulated and an oscillation-frequency, respectively, each of said circuits including the same variable condenser, and a fixed condenser included in one of said tuned circuits 65 for aligning the tuning of both of said circuits, whereby the frequency to which each of said circuits is tuned by variation of said variable condenser has a substantially constant difference, said fixed condenser being so proportioned as to 70 restrict passage of currents of the frequency of 75

one of said tuned circuits into the other of said circuits, and the inductance of one of said tuned circuits being so proportioned as to act as a radio-frequency choke with respect to the frequency produced in the other of said tuned circuits.

19. A radio-frequency circuit comprising a first 10 tuned circuit tunable to a desired radio frequency and comprising an inductance and a variable condenser, a second tuned circuit tunable to a different radio frequency, and including a second inductance, a fixed condenser, and said first-mentioned variable condenser, two thermionic vacuum tubes each having a pair of input terminals, a connection from one of said tuned 15 circuits to the input terminals of one of said vacuum tubes, and a connection from the second tuned circuit to the input terminals of the other of said vacuum tubes, whereby the frequencies of the currents impressed upon the input of each 20 of said vacuum tubes may be simultaneously varied in the same sense through different frequency bands by a variation of the capacity of said variable condenser.

20. A frequency-changing circuit which includes a first tuned circuit comprising an inductance and a variable condenser, a second 25 tuned circuit including a second inductance, a fixed condenser and said first-mentioned variable condenser and having reactive constants so proportioned with respect to those of said first 30 circuit that each of said circuits has a high impedance to currents of the frequency to which the other is resonant, two vacuum tubes each comprising input and output terminals, a connection between the first of said circuits and the input terminals of one of said vacuum tubes, a connection between the other of said circuits and the input terminals of the other of said 35 vacuum tubes, and a coupling between the output 40 terminals of one of said vacuum tubes and the input thereof, whereby said tube and its associated circuits operate as an oscillator and modulate currents impressed upon the input terminals of the other of said tubes.

21. A radio-frequency circuit comprising a first 45 circuit tunable over a desired range of radio frequencies, a second circuit tunable over a substantially equal range of substantially different 50 radio frequencies and having reactive constants so proportioned with respect to those of said first circuit that each of said circuits has a high impedance to currents of the frequency to which the other is resonant, and an adjustable re- 55 actance element common to said tunable circuits and effective to tune them in the same sense over their respective ranges.

22. A radio-frequency circuit comprising a first 60 circuit tunable over a desired range of radio frequencies, a second circuit tunable over a substantially equal range displaced with respect to said first-named range in the frequency scale and having reactive constants so proportioned with respect to those of said first circuit that each of said circuits has a high impedance to 65 currents of the frequency to which the other is resonant, and an adjustable condenser common to said tunable circuits and effective to tune them in the same sense over their respective ranges.

23. A radio-frequency coupling network includ- 70 ing a plurality of reactance elements, said network comprising component resonant portions having points of impedance maxima substantially displaced on the frequency scale, means for substantially eliminating reaction of said 75

component portions upon each other, and means for tuning said network over a desired range and for adjusting said points in the same sense and to equal extents comprising an adjustable reactance element common to said portions.

24. A radio-frequency coupling network including a plurality of reactance elements, said network comprising component resonant portions across which appear voltage maxima displaced on the frequency scale, means for substantially eliminating reaction of said component portions upon each other and means for tuning said network over a range of frequencies and maintaining a substantially constant frequency difference between said points of voltage maxima comprising an adjustable reactance element common to said portions.

25. A radio-frequency network comprising a first component resonant circuit, a second component resonant circuit having a point of maximum impedance displaced on the frequency scale with respect to that of said first circuit, means for substantially eliminating reaction of said component circuits upon each other, and means for simultaneously tuning said circuits over a range of frequencies and adjusting their points of maximum impedance in the same direction and to equal extents on the frequency scale comprising an adjustable reactance element common to said circuits.

26. A radio-frequency coupling system comprising a first resonant circuit, a second resonant circuit having reactive constants so proportioned with respect to those of said first circuit that each of said circuits has a high impedance to currents of the frequency to which the other is resonant, a circuit for supplying radio-frequency energy to said circuits, said circuits including impedance elements individual thereto across which appear voltage maxima displaced on the frequency scale,

means for simultaneously tuning said circuits over a range of frequencies and adjusting said points of maximum voltage in the same direction on the frequency scale comprising an adjustable reactance element common to said circuits, and output circuits coupled to said impedance elements.

27. A radio-frequency circuit comprising a first circuit tunable over a desired range of radio frequencies, a second circuit tunable over a range of substantially different radio frequencies and having reactive constants so proportioned with respect to those of said first circuit that each of said circuits has a high impedance to currents of the frequency to which the other is resonant, an adjustable reactance element common to said tunable circuits and effective to tune them over their respective ranges, electron-discharge means having two input circuits and an output circuit, said tunable circuits being individually connected to said input circuits, and a coupling between said output circuit and one of said input circuits, whereby said electron-discharge means and its associated circuits operate as an oscillator and modulate currents impressed upon the other of said input circuits.

28. A radio-frequency circuit comprising a first circuit tunable over a desired range of radio frequencies, a second circuit tunable over a range of substantially different radio frequencies and having reactive constants so proportioned with respect to those of said first circuit that each of said circuits has a high impedance to currents of the frequency to which the other is resonant, and an adjustable reactance element directly connected in circuit with, and common to, both of said tunable circuits and effective to tune them in the same sense over their respective ranges.
